UNITED STATES PATENT OFFICE

ANTONE BLAZIC, OF LOS ANGELES, CALIFORNIA

ARTIFICIAL TREE

Application filed December 18, 1928. Serial No. 326,712.

The present invention relates to artificial trees and has for its prime object to provide a structure somewhat in simulation of a tree and including a base with a staff or trunk rising therefrom and a basket frame on said staff or trunk for containing plants, shrubs, bulbs, etc.

A still further very important object of the invention resides in the provision of a device 10 of this nature which is simple in its construction, inexpensive to manufacture, strong and durable, attractive in appearance, thoroughly efficient and reliable in use, and otherwise well adapted to the purpose for which it is 15 designed.

With the above and numerous other objects in view as will appear as the description proceeds, the invention resides in certain novel features of construction, and in the combination 20 and arrangement of parts as will be hereinafter more fully described and claimed.

Figure 1 is an elevation of the device embodying the features of this invention,

Figure 2 is a vertical section therethrough, 25 Figure 3 is a transverse section taken substantially on the line 3—3 of Figure 2,

Figure 4 is a top plan view of the basket frame,

Figure 5 is an enlarged detail transverse 30 section therethrough, and

Figure 6 is a detail section taken substantially on the line 6—6 of Figure 5.

Referring to the drawing in detail it will be seen that the letter A denotes a base, letter 35 B a staff or trunk, and the letter C a basket frame. The base A may be of any preferred construction but as illustrated herein includes a vase 5 constructed of suitable material. The staff B may be of any preferred construction preferably to simulate somewhat the trunk of a tree and in the present instance includes a metal hollow core 6 fastened to the bottom of the vase 5 by a screw 7 or in any other suitable manner, so as to rise

45 upwardly from the vase and about this tube 5 is a casing 8 of suitable material such as concrete. A cap including a shank 9 threaded in the upper end of the core 6 has a cap plate 10 thereon. The basket C comprises a ring plate 11 with a plurality of arcuate

arms 12 fastened thereto as at 14 to radiate outwardly therefrom and then curve upwardly and have their upper ends fastened in any preferred manner to a ring 15.

A bracing ring 16 is secured to intermediate portions of the arms 12. The ring plates 11 provided with slots, openings or the like 18 and cap screws 20 extend therethrough and are engaged in the cap plate 10 so as to detachably mount the basket frame 60 C on the staff B.

It is preferable to fill the vase 5 with dirt as is indicated at 21. The basket frame provides a container in which any type of plant, bulb, tree, cactus etc. can be arranged for 65 beauty and convenience.

Obviously these trees may be made in any size to suit the type of plant desired. It is thought that the construction, utility and advantages of this invention will now be quite 70 apparent to those skilled in this art without a more detail description thereof.

The present embodiment of the invention has been described in considerable detail merely for the purposes of exemplification 75 since in actual practice it attains the features of advantage enumerated as desirable in the statement of the invention and the above description.

It will be apparent that changes in the 80 details of construction, and in the combination and arrangement of parts may be resorted to without departing from the spirit or scope of the invention as hereinafter claimed or sacrificing any of its advantages. 85

Having thus described my invention, what I claim as new is:

1. An artificial tree device of the class described including a base, a staff rising from the base, and a basket frame on the staff, said 90 basket frame including a plate with wire arms fixed thereto, radiating outwardly therefrom and curved upwardly and inwardly.

2. An artificial tree device of the class described including a base, a staff rising from the base, and a basket frame on the staff, said basket frame including a plate with wire arms fixed thereto, radiating outwardly 95 therefrom and curved upwardly and inwardly.

ly, a ring connecting the upper ends of the arms, and a ring connected to the intermediate portion of the arms.

3. An artificial tree device of the class described including a base, a staff comprising a hollow core with a casing thereabout, a cap plate having a shank threaded in the upper end of the core, a basket frame including a ring plate, screws fastening the ring plate to the cap plate, and arcuate arms having their lower ends fixed to the ring plate to radiate outwardly therefrom, curving upwardly and inwardly.

4. An artificial tree device of the class described including a base, a staff comprising a hollow core with a casing thereabout, a plate cap having a shank threaded in the upper end of the core, a basket frame including a ring plate, screws fastening the ring plate to the cap plate, arcuate arms having their lower ends fixed to the ring plate to radiate outwardly therefrom curving upwardly and inwardly, and a ring connecting the upper ends of the arms.

25 5. An artificial tree device of the class described including a base, a staff comprising a hollow core with a casing thereabout, a cap plate having a shank threaded in the upper end of the core, a basket frame including a ring plate, screws fastening the ring plate to the cap plate, arcuate arms having their lower ends fixed to the ring plate to radiate outwardly therefrom curving upwardly and inwardly, a ring connecting the upper ends of the arms, and a second ring connected to the intermediate portions of the arms.

6. An artificial tree device of the class described including a base, a staff comprising a hollow core with a casing thereabout, a cap plate having a shank threaded in the upper end of the core, a basket frame including a ring plate, screws fastening the ring plate to the cap plate, arcuate arms having their lower ends fixed to the ring plate to radiate outwardly therefrom curving upwardly and inwardly, a ring connecting the upper ends of the arms, a second ring connected to the intermediate portions of the arms, said base including a vase, and means detachably engaging the core with the bottom of the vase.

In testimony whereof I affix my signature.

ANTONE BLAZIC.
